FLUID PRESSURE PUMP

Richard H. Carr, Chicago, Ill., assignor to The Pure Oil Company, Chicago, Ill., a corporation of Ohio

Application December 24, 1934, Serial No. 759,036

6 Claims. (Cl. 184—27)

This invention relates to fluid pressure pumps and more particularly to force feed lubricators for the purpose of supplying lubricating fluid under pressure to working parts of mechanical devices.

Present types of force feed lubricators now in commercial use have several disadvantages. Leakage usually occurs between the plunger and cylinder wall resulting in low volumetric efficiency. One reason for such leakage is the large diameter of the cylinder bore relative to the length of the liquid seal formed between the plunger and cylinder wall. Another reason for leakage is the slow speed at which present type commercial lubricators operate during the delivery stroke. A still further contributing factor is the arrangement of the driving mechanism in such a manner as to produce side thrust with resultant wear between moving parts.

My invention is designed to overcome the disadvantages inherent in lubricators now available for commercial use. By utilizing a cylinder and piston of very small diameter in conjunction with a short and rapid spring actuated plunger stroke and an extremely long liquid seal, I have succeeded in obtaining a high volumetric efficiency. Moreover by constructing the lubricator in such manner as to permit the plunger to float freely in the working cylinder with the total actuating force on the plunger exerted in a direction parallel to the direction of movement thereof, the wear occasioned by the sliding surfaces is reduced to a minimum.

In addition to embodying the foregoing novel features, my invention also is concerned with a force feed lubricator or pump which is capable of adjustment without interruption of operation, whereby smaller quantities of oil can be delivered with a greater degree of positiveness at regular intervals than has been possible heretofore. This feature of my invention is highly advantageous in connection with lubrication of mechanisms requiring only a very small amount of lubricant.

One of the novel features of my invention resides in the mechanism by means of which a plunger is made to reciprocate in a cylinder bore whereby a measured charge of lubricant can be drawn into the cylinder and be rapidly discharged.

Another novel feature of the invention is the arrangement of the actuating mechanism and the plunger whereby the stroke of the plunger can be varied without affecting the normal stroke of

the actuating mechanism and without interrupting the operation of the lubricator.

Still another feature of the invention is the combination of spring actuating means and dash pot arrangement whereby the delivery stroke can take place rapidly at high pressure without undue shock to the device.

Further novelty will be apparent from the following description considered in conjunction with the accompanying drawing, of which

Fig. 1 is a plan view of the lubricator with the top of the reservoir removed.

Fig. 2 is a vertical cross sectional view of the lubricator which forms the subject matter for my invention.

Fig. 3 is a vertical front end view of a portion of the lubricator;

Fig. 4 is a perspective view of a discharge valve;

Fig. 5 is a plan view of the suction valve; and

Fig. 6 is a vertical view of the suction valve.

Referring to the drawing, the numeral 1 designates generally a reservoir which may be a metallic box having a heavy bottom 2 and a removable top 3 which may be fastened to the reservoir by means of screws 4. The lid or top 3 has an opening 5 therein in order to permit communication between the atmosphere and the inside of the reservoir whereby to maintain atmospheric pressure on the surface of the oil contained in the reservoir and to serve as an inlet for oil fed to the reservoir.

Mounted within the reservoir is the lubricating mechanism designated generally by the numeral 6. The mechanism 6 is rigidly mounted onto a plate 8 extending almost the entire length of the reservoir 1 and the plate is in turn fastened to the bottom 2 by means of bolts 10. The front or head end 12 of the lubricating mechanism is fastened to the plate 8 by means of bolts 14. An abutting member 16 is fastened to the plate 8 by means of bolts 18. The member 16 has a circular opening 19 of sufficiently large diameter to permit a part of the lubricating mechanism to reciprocate freely therein. The opening is of larger diameter than the diameter of the reciprocating member.

The head end 12 has a narrow vertical bore 20 which is counter-bored adjacent the ends thereof in order to receive suction valve 22 and discharge valve 24. The suction valve seat 26 is adapted to be screwed into the lower enlarged portion of the vertical bore 20, and the valve 22 is adapted to seat snugly against the upper end thereof. The valve seat 26 has a narrow bore 28 prefer-

ably corresponding to the diameter of the bore 20. The lower portion of the head end 12 between the bolts 14 is cut out at 29 so as to form a space between it and the plate 8 to allow free 5 passage of lubricant from the reservoir into the bore 20.

The upper enlarged end of the bore 20 has a valve 24 mounted therein which is adapted to seat tightly against the upwardly diverging faces 10 31 formed at the point where the bore 20 widens. A valve body and seat 32 is adapted to be screwed into the upper enlarged end of the bore 20. The lower portion of valve body 32 has a passage 34 corresponding in diameter to the bore 20 and is 15 counter-bored in the upper portion thereof to receive valve 35. The lower face of the valve 35 is adapted to fit snugly against the upper end of the passage 34. A second valve body and seat 36, corresponding to valve body and seat 32, is 20 adapted to be screwed into the upper end thereof. Valve body and seat 36 is adapted to receive and seat valve 37 in precisely the same manner as valve 35. A valve retainer plug 44 having a passage 46 preferably corresponding to the passage 25 34 is adapted to be screwed into the upper end of the valve body and seat 36.

The valves 22, 24, 35 and 37 may be octagonally sided as shown in Figs. 4 to 6, so as to allow sufficient space for oil to flow between the valve 30 body and the sides of the valves. The upper face 41 of the valve 22 is arcuate and the top of the valve has arcuate grooves 48 and 49 at right angles to each other in order to permit oil to pass the valve when it is raised during suction. The 35 arcuate grooves 48 and 49 are deepest where they meet the sides of the valve and shallowest in the middle. The bottom 50 is shaped like an inverted cone and is adapted to fit snugly against the bevelled upper edge of the suction valve seat 26. 40 The valves 24, 35 and 37 are identical with valve 22 with the exception that the upper faces thereof are flat instead of arcuate.

The head end 12 is adapted to fit snugly against the inner surface of front wall 54. A long cylindrical projection, to form pump cylinder member 55, extends horizontally from the rear of head end 12 and a somewhat shorter annular extension forms dash pot member 56 which surrounds the front end of member 55 and is spaced therefrom. The head end 12 and members 55 and 56 are preferably cast as a unitary structure from brass or other suitable metal or alloy. The outer surface of the member 55 and the inner surface of the annular extension 56 are machined to provide sliding surfaces for a sleeve to be subsequently described. A horizontal cylindrical bore of suitable diameter extends completely through the head end 12 and member 55 and the front end of the bore is closed by screw plug 58. The horizontal bore and bore 20 lie in the same vertical plane.

A plunger 70 is slidably mounted in the horizontal bore and adapted to reciprocate therein. The plunger 70 is provided with a shoulder 74 65 at a point a short distance behind the rear end of member 55. The rear end 76 of the plunger 70 is somewhat enlarged to receive a washer 78 which is held in place by means of nut 80 which may be screwed or otherwise attached to the end 70 of the plunger.

A sleeve member 81 is adapted to slide on the machined surfaces provided by member 55 and extension 56 and through the opening 19 in the abutting member 16. The sleeve is provided with 75 orifices 82 to permit access of lubricant to the

moving parts enclosed therein. At its front end the sleeve is provided with an annular piston 83 cast integrally therewith, which is adapted to be slidably mounted in the annular space between the member 55 and extension 56. Immediately 5 behind the annular piston 83 the sleeve is provided with an annular shoulder 84. The rear end of the sleeve extends approximately to the washer 78. The inner surface of the sleeve is provided with an inwardly extending annular shoulder 88 10 immediately behind the shoulder 74 of the plunger 70. A heavy coil spring 90 encircles the sleeve 81 and abuts against shoulder 84 at one end and the member 16 at the other. A lighter coil spring 92 encircles the rear end of the plunger 70 and 15 abuts against the shoulder 88 at one end and the washer 78 at the other.

A spacer block 94 is fastened to the bottom 2 by means of bolt 96 between the rear wall 98 of the reservoir 1 and the rear end of plate 8. A 20 detent adjusting screw 100 extends into the reservoir through the rear wall 98 and is mounted in a stuffing box gland 102 which in turn is fastened to the rear wall 98 by means of screws 104. A stuffing box gland nut 106 is mounted on stuffing box gland 102 outside the reservoir. The screw 100 is mounted directly in line with plunger 70.

A short shaft 108 extends through side wall 109 and is mounted in bearing 110 which in turn 30 is fastened to side wall 109 outside the reservoir 1 by means of screws 111. The inner end of the shaft is designated by the dotted line 112. A pawl lever 113 is mounted on shaft 108 inside the reservoir and adjacent the side wall 109. The lever 113 is keyed to shaft 108 and is adapted to oscillate integrally therewith. A ratchet wheel 114 is mounted on shaft 108 immediately adjacent lever 113 and is adapted to rotate independently of shaft 108. Driving pawl 115 is rotatably mounted at the end of pawl lever 113 by means of screw 116. The pawl is held against ratchet wheel 114 by means of a spring not shown. A brake pawl 117 is rotatably mounted on the inside of side wall 109 by means of screw 118 which in 40 turn is screwed into support 119. The support 119 is fastened to the side wall 109 by means of screw 120. The pawl 117 is held against the ratchet wheel 114 by means of a spring not shown. The pawls 115 and 117 are adapted to 50 engage the teeth 121 of the ratchet wheel 114.

A second shaft 122 of greater diameter than shaft 108 is recessed concentrically at 123 to provide bearing surface for the inner end of shaft 108. The inner end 112 of shaft 108 is inserted 55 in the recess 123 and is adapted to rotate therein independently of the shaft 122. The end 124 of shaft 122 extends to a point adjacent the side of ratchet wheel 114 and holds the wheel in place. The opposite end 125 of shaft 122 is adapted to 60 rotate in bearing 126 which is fastened to side wall 127 by means of screws 128. The ratchet wheel 114 is keyed to the shaft 122 by means of key 129 and rotates integrally therewith. A cam 130 is keyed to shaft 122 at a point immediately 65 above shoulder 84. The shaft 122 is located above shoulder 84 and slightly forward thereof in order that the cam 130 may co-act therewith. The shaft 108 is adapted to be oscillated by any suitable driving mechanism. It will be apparent that 70 other suitable actuating mechanism may be used in place of that shown and described herein and the specific actuating mechanism shown and described is by way of illustration only.

A sight feed indicator 132 for observing the 75

quantity and rate of flow of lubricant delivered by the lubricator is attached to the discharge line 135 by means of a suitable coupling 136.

The operation of the lubricator is as follows:

- 5 The shaft 108 is oscillated by means of any suitable actuating mechanism. The lever 113 being keyed to the shaft 108 oscillates therewith and at each stroke the driving pawl 115 rotates the ratchet wheel 114 a short distance in the direction indicated by the arrows in Fig. 2. The brake pawl 117 acts as a detent to prevent the ratchet wheel from rotating in the opposite direction. The operation of the ratchet wheel causes shaft 122 to slowly rotate and the rotation 10 of the shaft 122 brings the cam 130 into contact with the shoulder 84, causing it to move backward against the compression of the spring 90. The rearward movement of the sleeve tends to compress spring 92 which in turn causes the plunger 20 to move backward. The backward movement of the plunger 70 draws lubricating oil from the reservoir 1 through orifice 28, past valve 22 into bore 20 and then into the horizontal cylinder or bore formed in the member 55 in which the plunger 70 reciprocates. The entire stroke or distance through which the sleeve 81 and the plunger 70 reciprocate may be approximately $\frac{1}{2}$ inch. At the same time that lubricant is drawn into the cylinder, lubricant is also drawn through orifice 30 66 into the annular space formed between the member 55, extension 56 and annular piston 83. This space forms a dash pot. As the cam 130 continues to rotate it moves past the top of the shoulder 84 suddenly releasing it. The coil spring 35 90 drives the sleeve forward and the shoulder 88 of the sleeve pushing against the shoulder 74 of the plunger drives the plunger forward along with the sleeve. The lubricant in the annular space or dash pot between the member 55 and extension 56 is forced out through the small orifice 66 and takes up the shock of the forward movement of the sleeve. The diameter of the orifice 66 is small enough to offer sufficient resistance to the discharge of oil from the dash 40 45 pot so that the oil has a cushioning effect. It is evident that a valve controlled passage may be used instead.

The lubricant contained in the horizontal bore or cylinder is suddenly driven out through discharge valves 24, 35 and 37 through discharge line 135 and sight indicator 132 to the desired points. The rapidity with which the lubricant is discharged minimizes leakage and enables a positive quantity of lubricant to be delivered at high pressures. The cam 130 continues on its journey around with the shaft 122 until it again meets the shoulder 84 and begins another suction stroke of the lubricator.

Due to the small bore in which plunger 70 reciprocates, the required compression of the spring 90 is relatively low. For example, with a bore of $\frac{3}{16}$ of an inch, a coil spring having a compression of approximately 28 pounds at the beginning of the discharge stroke is sufficient to deliver oil under a pressure of 750 pounds per square inch. The maximum compression of the spring 92 at the beginning of the discharge stroke may be approximately 10 pounds and should be sufficient to carry the plunger 70 the entire suction stroke traveled by the sleeve 81 when the plunger is not detented by the screw 100. Although I have found that a cylinder of approximately 4 inches in length and $\frac{3}{16}$ of an inch diameter gives very satisfactory results with a plunger having a maximum stroke of $\frac{1}{2}$ inch,

it will be understood that the length of the cylinder may be greater and the diameter of the bore and the compression of the spring 90 may be varied to secure any desired delivery pressure.

In order to regulate the quantity of lubricant delivered by the lubricator, the stroke of the plunger 70 may be varied by means of the detent adjusting screw 100. If it is desired to feed the maximum quantity per stroke that is possible, the screw is placed in such a position that it will not abut the rear end of the plunger 70 when the sleeve 81 is at the end of the suction stroke. This permits the plunger 70 to travel to its full length stroke along with the sleeve. However, if it is desired to decrease the amount of lubricant delivered, the screw 100 is screwed inwardly until it will abut the rear end of the plunger 70 before the plunger reaches its most rearward position on the suction stroke. The stroke of the sleeve 81 continues as usual but the stroke of the plunger 70 is shortened and the difference in stroke is taken up by the coil spring 92. When the cam 130 releases the sleeve 81 the coil springs 90 and 92 drive the sleeve forward until the shoulder 88 thereof abuts the shoulder 74 of the plunger and the two then move forward in unison to discharge the lubricant.

It will be seen that I have devised a novel means for force feed lubrication which is capable of flexible and long dependable operation due to its relatively simple structure and provision of means for eliminating to a great extent excessive wear on moving parts.

What I claim is:

1. A force feed lubricator comprising a cylinder, 35 a plunger slidably mounted therein, a sleeve surrounding said cylinder, an annular cylinder in which said sleeve reciprocates, a passageway communicating with said first mentioned cylinder through which fluid can be drawn and discharged, a passageway communicating with said annular cylinder through which fluid can be drawn and discharged, cam mechanism for actuating the sleeve during its suction stroke, a spring for actuating the sleeve during the discharge stroke, means for yieldingly actuating the plunger by means of the sleeve during the suction stroke and means for actuating the plunger by means of the sleeve during the discharge stroke.

2. A force feed lubricator comprising a cylinder, 50 a plunger slidably mounted therein, a sleeve surrounding said cylinder, an annular cylinder in which said sleeve reciprocates, a passageway communicating with said first mentioned cylinder through which fluid can be drawn and discharged, 55 a passageway communicating with said annular cylinder through which fluid can be drawn and discharged, cam mechanism for actuating the sleeve during its suction stroke, a spring for actuating the sleeve during the discharge stroke, an inwardly extending abutment on said sleeve and an outwardly extending abutment on said plunger immediately in front of said sleeve abutment and adapted to engage against it, a coil spring surrounding said plunger and abutting 60 between said sleeve abutment and an abutment fastened adjacent the end of said plunger, and means for shortening the suction stroke of the plunger without affecting the stroke of the sleeve member.

3. A fluid pump comprising a cylinder, a plunger slidably mounted in the cylinder, a reciprocable sleeve mounted concentrically of said plunger and cylinder, said plunger being adapted to be actuated by said sleeve and said sleeve being 75

freely spring actuated on the delivery stroke, and fluid cushioning means for reducing the shock of the delivery stroke of said sleeve comprising an annular cylinder in which the forward end 5 of said sleeve is adapted to slide, said annular cylinder being closed at one end and having a restricted opening adjacent said closed end.

4. A force feed lubricator comprising a casing, a horizontally disposed pumping unit mounted 10 on the bottom of said casing, said unit comprising an elongated cylinder, a plunger slidably mounted in said cylinder, a sleeve slidably mounted on the outer surface of said cylinder, a collar on said sleeve adjacent the forward end thereof, 15 an annular cylinder having a restricted opening at one end and in which the forward end of said sleeve is slidably mounted, an abutting member adjacent the rear end of said pumping unit, a coil spring surrounding said sleeve and abutting 20 said collar and abutting member, a driving shaft, a cam on said shaft adapted to engage said collar

and operate said sleeve, and means operable to reciprocate said plunger by means of said sleeve.

5. A force feed lubricator comprising a cylinder, a piston slidably mounted in said cylinder, a sleeve slidably mounted on said cylinder, said sleeve being in operative engagement with said piston, an annular cylinder in which the forward end of said sleeve is slidably mounted, a restricted opening adjacent one end of said annular cylinder, and driving means operable to reciprocate 10 said sleeve and said piston.

6. Means for cushioning the end of the forward stroke of a spring actuated reciprocable sleeve member arranged to actuate a pump plunger comprising an annular cylinder in which the forward end of said sleeve member fits snugly and is adapted to slide therein, said cylinder being closed at one end and having a restricted opening adjacent said closed end.
